UNITED STATES PATENT OFFICE

1,932,582

GAS SAMPLING APPARATUS

Gaylord H. Halvorson, Duluth, Minn.

Application May 16, 1927. Serial No. 191,911

3 Claims. (Cl. 23—257)

The invention pertains to a gas sampling apparatus, and more particularly to one for taking samples of a gas at predetermined intervals during a long determined period of time.

5 An object of the invention is to provide a simple, inexpensive and compact gas sampling apparatus for intermittently sampling gas for any suitable and chosen period of time.

Another object is to provide a device to obtain 10 a uniform pressure in a part thereof preceding the gas sampling container regardless of any line pressure that may exist.

Still another object is to provide a device to bleed gas in sufficient quantities so that a representative sample is obtained even though the sampling apparatus may be located at some distance from the gas main.

A further object is to provide a gas sampling device to sample a representative amount of gas 20 from a main, said device being of such character that there can be no backing up of fluids in the device.

With these and various other objects in view, the invention may consist of certain novel features of construction and operation, as will be 25 more fully described and particularly pointed out in the specification, drawing and claims appended hereto.

In the drawing, the figure is a more or less 30 diagrammatic sectional elevation of certain parts of the device.

A gas inlet pipe 1 communicates through a one-way water seal 2 to a substantially W-shaped pipe 3, 4, 12. The W-shaped pipe has 35 its center leg 4 extending into a container receptacle 5, which is sealed by any suitable means, as plug 25, except for apertures for the inlet and outlet connections. Said container has a float valve 6 movable on suitable guides 6^b and 40 has a mercury seal 6^a in the top thereof. Said valve cooperates with a gas overflow or waste pipe 8 which is connected through a one-way water seal 9 to the exhaust pipe 10 communicating with the atmosphere. From adjacent the 45 bottom of the container 5, there extends a waste water pipe 7, the free end of which extends below the level of liquid in the bottom of the container 5. Another pipe 11 communicates with the container 5 for the introduction of water 50 thereto.

The other leg 12 of the W-shaped pipe is connected to a pipe 14 by means of a one-way water seal 13, the pipe 14 communicating to a container 16 through any suitable plug or sealing means 55 26. This pipe 14 is provided with any shut-off

control, such as a pinch valve 15 for controlling the flow of gas to this container 16. The container 16 is connected by a suitable pipe 17 extending adjacent the bottom of the container 16 and which includes a flexible part 17^a and communicates with a movable container 18 through a sealing plug 27, said pipe extending to points adjacent the bottom of both of the containers 16 and 18. The container 16 is also provided with a gas outlet pipe 20 provided with any control cock 20^a. The container 18 is raised or lowered through any suitable time operating means, such as a clock-drum-cable arrangement as indicated at 19 and the container may be guided between suitable fixed guides 21 positioned on the base 24 of the device, the container having suitable spacers 22 of any construction, such as will allow free sliding movement of the container 18. This container 18 is also provided with an air vent 23 in the top thereof.

It will also be noticed that one-way water seals are provided with the sealing plugs 28, 29 and 30 in the seals 2, 9 and 13 respectively, said plugs being suitably apertured to provide for their respective inlet and outlet pipes. It will also be seen that when the valve 6 seals the gas outlet pipe 8 that there is established a head A which is greater than that head established at B by the water levels of the containers 18 and 16.

In operation, gas to be sampled flows from the source through the inlet pipe 1 through the water seal 2 up into the pipe 3. From there it flows into pipe 4 into the container 5. Also, a portion thereof will flow through the branch 12 into the water seal 13, but will not flow into the sampling container 16 as that container is full of water, or the cock 15 can be closed until flow is established through container 5. At the same time that the gas is introduced into the container 5, at a substantially constant rate water is being introduced to said container through the pipe 11. This water will gradually raise the float valve 6 in such time that it seals the gas outlet pipe 8. Before this is sealed, the gas will flow through the pipe 4 out of the pipe 8 through the water seal 9 and out the exhaust pipe 10, this being a line of less resistance than through the pipe 12 through the water seal 13 through the pipe 14 and into the container 16 where it would have to displace water in that container to the then raised container 18.

As the water rises and seals the pipe 8 through the valve 6 and the mercury seal 6^a thereof, the inflowing gas and water build up a pressure of the gas trapped in the container 5 to a point whereby a siphon is caused to be formed between the con-

tainer and the pipe 7, which will empty this container 5. The siphon determines the head A and this head means that during each cycle, a gas pressure of A is applied to the line 3 regardless of 5 this line pressure. The gas pressure in the line or branch outlet 3 normally balances the head of water B between the movable and fixed containers 18 and 16 respectively, at the seal 13. When, however, the float 6 is raised by the water entering 10 the container 5, thereby sealing the gas waste pipe 8, the pressure of A is maintained in pipe 3, this pressure A being determined greater than the pressure represented by the constant head B. The pressure then in lines 3, 12 will overcome the 15 pressure caused by head B, causing the gas to flow through the seal 13 into the pipe 14 and if the pinch valve is opened, into the container 16 displacing water into container 18. A continued flow of gas will continually displace the water in this 20 container causing it to flow through the pipe 17 through the flexible connection 17^a and into the container 18. The water head B is maintained constant by lowering the container 18 by means of the clock arrangement 19, which is timed to 25 correctly operate the container. This is an established head so that there will be a proper flow from container 16 to container 18, the head B being less than head A, it being necessary that this condition exists at the time the valve 6 seals 30 to prevent entrance of gas to container 5.

It will be seen that the water entering the container 5 will intermittently operate the valve 6 to close the overflow pipe 8; therefore, the gas will only intermittently flow to the container 16, 35 which means that gas is periodically taken from the main into the container 16 and there drawn off at will through the pipe 20.

In collecting a sample of the gas by displacement of water, it will be seen that it is necessary 40 to have a uniform flow of water from the gas sampling container 16 to the movable or water receiving container 18, and as the introduction of the gas depends upon a difference in the heads A and B, it is therefore necessary to carry a back pressure 45 in the container 16 so that pressure differential is such that an amount of gas passes the seal 13 at each interval proportionate to the drop of the movable container during that interval. This back pressure varies with the length of time 50 between the applications of pressure in line 3. This means that it depends upon the rate of flow of water into the container 5 and should be adjusted when the apparatus is started so that no change takes place during the sampling operation. If the apparatus is started with too high 55 a back pressure, a smaller amount of gas passes the seal 13 at each interval until the proper back pressure is established. By operating the apparatus a short time (until an equilibrium has been 60 established), the correct back pressure has been determined for any rate of flow of water with the same back pressure throughout the sampling period. The rate of flow of the gas into the gas sampling bottle must be uniform at all times.

65 With sampling low pressure gas, such as producer gas, or when sampling gas caused by a stack draft, such as flue gas, the operation is slightly different. At such times, the gas is drawn into the container 5 by the suction produced when the 70 water is removed through the pipe 7 due to the siphon action. When the siphon is broken, the gas is forced through the outlet as the incoming water builds up in the container. This continues

until the float 6 rises and the mercury seal 6^a closes the outlet of the pipe 8, when the incoming water builds up the pressure of the trapped gas to A, causing the siphon to again form.

It will be seen that with the water seals, the 80 gas is only allowed to flow one way, as indicated by the arrows, so that gas coming from pipe 1 can only go to the pipe 3 and not in a reverse direction; gas can only go from pipe 8 to pipe 10, and similarly, gas can only go from pipe 12 to the 85 pipe 14.

I do not wish to be limited by the exact apparatus or operation shown and described as other and various forms will be apparent to those skilled in the art.

90 I claim:

1. In gas sampling apparatus, the combination of a pair of gas receiving containers, the second of said containers being normally filled with water, a connection from a source of supply to each of said containers, means for preventing flow from the second of said containers to the first of said containers, a water inlet into said first container for supplying water thereto, an outlet from said container, said outlet being disposed to form a siphon whereby said container may be emptied of water, a gas exhaust from said container operative to prevent supply of gas to said second container, a float valve operated by the water level in said first container 100 to close the exhaust from said container whereby the siphon is set up to form an effective head to cause supply of gas to said second container, a movable receptacle connected to said second container whereby water may be forced into said 110 receptacle by gas supplied to said second container, means for moving said receptacle at a selected rate whereby water supplied to said receptacle forms a head to be overcome by said first named head before gas is permitted to be 115 supplied to said second container, and a gas draw-off connection from said second container.

2. In a gas sampling device, the combination of a pair of connected containers, one of said containers having an inlet connection for admitting 120 liquid thereto, said containers being connected by inlet means for introducing gas serially to said containers, a siphon outlet for draining liquid from said first-named container, an outlet connection for normally conducting said gas 125 from said first-named container, and a member controlled by the liquid level in said first-named container for causing said gas to be supplied through said inlet means to said second-named container.

3. In a gas sampling device, the combination of a pair of connected containers, one of said containers having an inlet connection for admitting liquid thereto, said containers being connected by inlet means for introducing gas serially 135 to said containers, a siphon outlet for draining liquid from said first-named container, an outlet connection for normally conducting said gas from said first-named container, and a member controlled by the liquid level in said first-named 140 container for causing said gas to be supplied through said inlet means to said second-named container, continued supply of liquid causing said siphon to discharge liquid from said first-named container whereby said member is operated to 145 cause the gas to be supplied to said first-named container.

GAYLORD H. HALVORSON.
